UNITED STATES PATENT OFFICE

OSCAR GREENWALD, OF BROOKLYN, NEW YORK, ASSIGNOR TO FAICHNEY INSTRUMENT CORPORATION, OF WATERTOWN, NEW YORK, A CORPORATION OF NEW YORK

POCKET-THERMOMETER CASE

Application filed December 15, 1927. Serial No. 240,087.

This invention relates to improvements in pocket thermometer cases for the use of physicians in carrying thermometers. More particularly this invention relates to improvements in fountain pen type cases or containers for thermometers.

The object of the invention is to provide an improved holding member or spring member adapted to be inserted in the standard type and size fountain pen pocket thermometer case for the purpose of preventing the thermometers from rattling and breaking.

My improved pocket thermometer case is characterized by the fact that a single resilient holding member is interposed between the thermometers whereby a more efficient and more economical type of holding member is provided.

Accordingly my invention is embodied in a pocket thermometer pocket case constructed and arranged as hereinafter set forth and as illustrated in its preferred form in the accompanying drawing in which

Figure 1 is a view of the pocket thermometer casing, with parts in section.

Figure 2 is a perspective view of the spring holding member.

Figure 3 is a plan view of the cap which carries the member.

In the drawing the reference numeral 4 denotes the barrel of a fountain pen which may be closed by the well known type of clip cap

5. In the mouth of the barrel there is inserted a plug or cap 6 having two apertures

35 7 and 8. The plug 6 further carries a holding and separating member 9 in the form of thin strip or blade preferably of spring brass.

The blade 9 is cut to provide two springs 11 and 12 which are bent outward from the blade substantially parallel therewith. The springs are bent in opposite directions so that the spring 11 is on one side of the blade and the spring 12 on the opposite side of the blade.

45 The plug 6 and blade 9 form a separating and holding member which is inserted in the barrel 4, the plug 6 fitting tightly in the mouth of the barrel. The numerals 13 and 14 denote two thermometers, the grading of

55 In use the thermometers are inserted in the apertures 7 and 8 and pushed into the barrel. In passing into the barrel, the thermometers depress the springs, which latter engage the thermometers with sufficient spring pressure to separate and hold the thermometer firmly in the barrel 4. When the thermometers are withdrawn, the springs 60 spring outward from the blade, but are again easily depressed when the thermometers are reinserted.

The blade member is cut and shaped in a single operation and inserted in a groove 15 in the plug 6 in which it is held firmly.

It is obvious that the invention is not 65 limited in its use to fountain pen type pocket thermometer casings but may be used for other purposes.

I claim:

A thermometer casing including a barrel 70 formed to contain a pair of thermometers, a plug in the barrel provided with apertures to receive the thermometers therethrough, and a member secured to the plug and disposed in the barrel between the apertures, said member having spaced integral tongues struck out therefrom, one of the tongues being connected to the member adjacent an end of the latter and the other tongue being connected to the member adjacent to the center of the length 75 of said member, the tongues being disposed on opposite sides of the member.

OSCAR GREENWALD.
